UNITED STATES PATENT OFFICE

126,201

DESIGN FOR A SHOE OR SIMILAR ARTICLE

Newton Elkin, Philadelphia, Pa.

Application February 11, 1941, Serial No. 98,910

Term of patent 3½ years

To all whom it may concern:

Be it known that I, Newton Elkin, a citizen of the United States, residing in Philadelphia, in the county of Philadelphia and in the State of Pennsylvania, have invented a new, original, and ornamental Design for a Shoe or Similar Article, of which the following is a specification, reference being had to the accompanying drawing, forming part thereof.

I claim:

The ornamental design for a shoe or similar article, substantially as shown.

NEWTON ELKIN.
